UNITED STATES PATENT OFFICE.

WILHELM B. BRONANDER, OF BROOKLYN, NEW YORK, ASSIGNOR TO INTERNATIONAL CIGAR MACHINERY COMPANY, A CORPORATION OF NEW JERSEY.

SINGLE-ACTUATOR CIGAR-BUNCH SHAPER.

Application filed November 26, 1923, Serial No. 676,977. Renewed September 29, 1925.

To all whom it may concern:

Be it known that I, WILHELM B. BRONANDER, a citizen of the United States, residing at Brooklyn, county of Kings, and State 5 of New York, have invented a new and useful Improvement in Single-Actuator Cigar-Bunch Shapers, of which the following is a specification.

This invention relates to an improvement 10 in cigar bunch shaping mechanisms and it has for its main object the simplification of mechanisms of this character whereby cost of construction and maintenance is decreased and efficiency is increased. With 15 this and other objects not specifically mentioned in view, the invention consists in certain constructions and combinations which will be hereinafter fully described and then specifically pointed out in the claims here- 20 unto appended.

In the accompanying drawings, which form a part of this specification and in which like characters of reference indicate the same or like parts, Fig. 1 is a side elevation of a device constructed in accordance with the invention, with certain parts removed; Figs. 2, 3 and 4 are similar views showing the parts in different relation; Figs. 5 and 6 are opposite end elevations of the 30 structure shown in Figs. 1 to 4 inclusive; and Fig. 7 is a fragmentary plan view of the shaping members when in coacting position.

In carrying the invention into effect, there is provided a single cam-controlled actuator, a plurality of shaping members, and interposed operating connections whereby movement of the actuator produces movements of the shaping members to cause them to coact on the ends of a cigar bunch. In the best 40 constructions, the operating connections move a part of said shaping members in one direction, and the other part in another direction. In the best constructions also, bunch trimming means are provided, and this means also is operated by the same cam-controlled actuator, and interposed operating connections. The parts above mentioned 45 may be widely varied in construction within the scope of the claims for the particular device selected to illustrate the invention is

but one of many possible concrete embodiments of the same. The invention therefore is not to be restricted to the precise details of the structure shown and described.

Referring to the drawings, 8 indicates a 55 shaping mechanism bracket adapted to be mounted on the cigar machine in connection with which it is used. Pivotedly mounted on the bracket 8 is an actuator 9, which has a rocking movement produced by a link 60 10 pivoted to one end of a lever 11, which carries a cam bowl 12 tracking on a cam not shown but mounted on one of the cam shafts of the cigar machine in connection with which this mechanism is used. 65

The bracket 8 is provided with a vertical aperture in which a post 13 is mounted to slide. On the upper end of this post a head 14 is formed, and to this head are bolted two shaping members 15 adapted to act upon opposite ends of a cigar bunch. 70

At a point near the top of the bracket 8 a shaft 16 is journaled therein, and upon this shaft is pivoted a swinging bracket 17 having a head 18 at its upper end to which is bolted two more shaping members 15 complementary to those carried by the head 14 and adapted to coact with the first two shaping members when brought into proper relationship therewith. 80

Operative connections are interposed between the actuator 9 and the shaping members 15 for moving them in and out of coacting relationship, a part of said members being moved in one direction and a part in another direction. As shown, the shaping members 15 which are bolted to the head 14 are given a reciprocating movement by means of a link 19, one end of which is pivoted at 20 to a boss 21 formed on the 90 head 14. The other end of the link 19 is pivotally connected at 22 to the actuator 9 before referred to. At the proper time, the actuator 9 is rocked on its pivot, and this rocking movement actuates the link 19, 95 which, in turn raises or lowers the post 13, the head 14 and two of the shaping members 15, as the case may be.

The actuator 9 is provided with a cam surface 23—24, the former being nearly radial 100

and the latter being concentric with the pivot upon which the actuator rocks. This cam surface is in contact with a cam bowl 25 carried on the lower end of the swinging bracket 17, and when the actuator 9 is rocked this cam device serves to swing the bracket 17 from the position shown in Fig. 1 to the position shown in Fig. 2 during the first part of its movement, and to hold it 10 in the latter position during the latter part of its movement. A spring 26, the ends of which are respectively connected to a stud 27 on the bracket 17 and to a stud 28 formed on the end of the actuator pivot, serves to 15 hold the cam bowl 25 in contact with the cam surface 23—24 at all times. A cigar bunch is introduced between the shaping members while the parts are in the position shown in Fig. 1. The rocking movement 20 of the cam-controlled actuator 9 then begins, and the members 15 carried by the head 14 are raised to the position shown in Fig. 2, while the shaping members 15 carried by the swinging bracket 17 are swung into the 25 position shown in Fig. 2. A further rocking movement of the actuator in the same direction results in elevating the shaping members carried by the head 14 to their uppermost position, the other shaping members 30 being held stationary by the rolling contact of the cam bowl 25 on the cam surface 24. In this position the bunch is shaped, and upon a reverse rocking movement of the actuator 9 the shaping members are separated 35 in order that the bunch may be taken from between them. There is further provided bunch trimming means, and this means is also operated by the same cam-controlled actuator which operates the shaping members. 40 In the mechanism shown, both ends of the bunch are trimmed and consequently there are two bunch trimming members marked 29. One of the trimming members 29 is screwed to the upper end of an arm 30, fast on the shaft 45 16 before referred to; the other one is screwed to the upper end of a lever 31 also fast on the shaft 16. This lever 31 has a short arm 32 which lies in the path of a stud 33 carried on an arm 34 formed on the actuator 9. A stop 35 adjustably secured in a boss 36 formed on the lever 17 limits the movement of the lever 31 in one direction, and the lever is normally held against this 50 stop by the action of a thrust spring 37 of well known construction and operation.

When the parts have reached the position shown in Fig. 3, the shaping members remain stationary because the cam bowl 25 is then rolling on the cam surface 24 and the pivot 22 is almost in line with the fulcrum of the actuator and the pivot 20. At this 60 time the pin 33 has come into engagement with a short arm 32 of the lever 31 and a little farther rocking movement of the actuator 9 to the position shown in Fig. 4

throws the trimming members into operation. When the actuator has rocked in the opposite direction the trimming means is first thrust back to its normal position, then the post 13 is lowered, and during the latter 70 part of its down movement the bracket 17 is swung outwardly to release the shaped bunch.

In view of the foregoing, a detailed description of the operation of the device is 75 deemed unnecessary and is therefore omitted in the interest of brevity.

What is claimed is:

1. A cigar bunch shaping mechanism comprising a single cam-controlled actuator, a 80 plurality of shaping members, and interposed operating connections including a cam device operating a part of said shaping members.

2. A cigar bunch shaping mechanism comprising a single cam-controlled actuator, a plurality of shaping members, and interposed operating connections including a link connecting said actuator with a part of said shaping members and a cam device operating 90 the other part of said shaping members.

3. A cigar bunch shaping mechanism comprising a single cam-controlled actuator, a plurality of shaping members, and interposed operating connections moving a part 95 of said shaping members in one direction and the other part of said shaping members in another direction.

4. A cigar bunch shaping mechanism comprising a single cam-controlled actuator, a 100 plurality of shaping members, and interposed operating connections reciprocating a part of said shaping members and swinging the other part of said shaping members in and out of coacting relationship. 105

5. A cigar bunch shaping mechanism comprising a single cam-controlled actuator, a plurality of shaping members, bunch trimming means, and interposed operating connections. 110

6. A cigar bunch shaping mechanism comprising a single cam-controlled actuator, a plurality of shaping members, bunch trimming means, and interposed operating connections including a cam device operating 115 said trimming means.

7. A cigar bunch shaping mechanism comprising a single cam-controlled actuator, a plurality of shaping members, a plurality of trimming members, and interposed operating connections including a link connecting said actuator with a part of said shaping members and a cam device operating the other part of said shaping members and a cam device operating said trimming members. 120

8. A cigar bunch shaping mechanism consisting of a single cam-controlled actuator, a plurality of shaping members, and interposed operating connections. 130

9. A cigar bunch shaping mechanism consisting of a single cam-controlled actuator, a plurality of shaping members, and interposed operating connections, said actuator having a rocking operating movement.

10. A cigar bunch shaping mechanism consisting of a single cam-controlled actuator,

a plurality of shaping members, and interposed operating connections including a link connecting said actuator with a part of said shaping members. 10

In testimony whereof, I have signed my name to this specification.

WILHELM B. BRONANDER.
